Attorney.

UNITED STATES PATENT OFFICE.

ALVIN J. MARSHALL, OF LYNN, MASSACHUSETTS.

BANDAGE.

1,315,319.

Specification of Letters Patent.

Patented Sept. 9, 1919.

Application filed May 8, 1919. Serial No. 295,641.

To all whom it may concern:

Be it known that I, ALVIN J. MARSHALL, a citizen of the United States, residing at Lynn, in the county of Essex and State of 5 Massachusetts, have invented certain new and useful Improvements in Bandages, of which the following is a specification.

This invention relates to bandages which comprise a belt and a shield or pad held 10 in position by the belt; and it consists in the novel construction and combination of the parts hereinafter fully described and claimed whereby a shield or pad is held securely in position and without any lump 15 or projection being formed by the belt and its connections at the back of the wearer.

In the drawings, Figure 1 is a side view of a bandage constructed according to this invention. Fig. 2 is a front view, Fig. 3 20 is a rear view, and Fig. 4 is a plan view, of the bandage. Fig. 5 is a cross-section through the shield or pad, taken on the line 4—4 in Fig. 4. Fig. 6 is a detail view showing the connection of the pad or shield 25 with the sling.

The belt 3 is formed of any approved textile material which is light and strong, and its edges are reinforced with tape 4 which is sewed to them. The belt is provided with 30 a front apron 5 and a rear apron 6, and it has a fastening 7 at one side where its ends meet. This fastening may be a button and button-hole, or any other suitable connection.

35 A sling 8 is provided, and is suspended between the two depending aprons. This sling is formed of a band of textile material having reinforced edges similar to the belt and its aprons, and the side portions 40 9 of its front and rear portions are folded over or doubled, and the rear portion has longitudinal plaits 10 formed in it where

it is joined to the rear apron. The sling is sewed to the rear apron, and 12 is a cover piece formed of textile material and sewed 45 to the apron over the end of the sling.

This cover piece strengthens the attachment, and does not form any lump or projection of an objectionable sort, and the flexible apron fits snugly against the back 50 portion of the body of the wearer. The pad or shield 14 is formed of gauze and is a flattened bag packed loosely with cotton 15 or other absorbent material. The overlapping portions 9 of the sling have loops 55 16 of tape sewed to them, and the ends of the pad or shield have strings of tape 17 secured to them and arranged in pairs. These strings are passed through the loops 16 and are tied together as shown in Fig. 60 6. The end portions of the pad or shield are held in the folded portions 9 of the sling.

A fastening device or buckle 18 of any approved construction is provided for connecting the front end of the sling to the 65 front apron, and a safety-pin may be used for that purpose.

The bandage is easily adjusted to the wearer, and the pad or shield can be renewed as often as necessary with great facility. 70

What I claim is:

In a bandage, a belt, a sling having its front and rear portions connected to the belt, a pad supported by the sling, loops secured to the side portions of the sling at 75 the ends of the said pad, and tie strings passing through the said loops and connected to the said pad, said strings operating to secure the side portions of the sling over the end portions of the pad and also to prevent the pad from sliding longitudinally. 80

In testimony whereof I have affixed my signature.

ALVIN J. MARSHALL.
